ELECTRIC GRILL

Burton E. Shaw, Cambridge, and Roger K. Lee, Jr.,
Watertown, Mass., assignors to Electronics Corporation of America, Cambridge, Mass., a corporation of Massachusetts

Filed Jan. 4, 1960, Ser. No. 58,924

Term of patent 14 years

(Cl. D81—10)

FIG - 1

Figure 1 is a perspective view of an electric grill embodying our new design;

We claim:

The ornamental design for electric grill, substantially as shown.
